UNITED STATES PATENT OFFICE

HERBERT DE STAEBLER, OF WEBSTER GROVES, MISSOURI

HIDE STRETCHER

Application filed March 29, 1930. Serial No. 440,036.

My invention relates to hide stretchers and more particularly to such devices used in the preparation of leather for the manufacture of belting and the like.

5 It is the practice in the art to trim the hide straight on the two sides and one end, while the other or neck end is left with an irregular edge. If the butt of leather resulting from the stretching operation is 10 to have uniform strength and elasticity throughout its area it is necessary to stretch the different longitudinally extending portions of the width of the hide separately because these portions can be stretched 15 different distances. For instance, a portion of the hide extending longitudinally along the backside thereof will be stretched only slightly by a given tension or pull while, on the other hand, a longitudinally extending portion at the bellyside of the hide will be stretched very much by the same tension or pull and must be so stretched if the resultant leather in that portion will have the 20 same strength and elasticity as the portion 25 on the backside of the hide. The longitudinally extending portions between the back and belly sides likewise must be stretched to different degrees varying in direct relation to their position in respect to the back or 30 belly side.

In the stretching machines and the stretching operations including them as heretofore used the straight edge of the hide at the end thereof opposite the neck or irregular end 35 was held in a stretching frame by means of a fixed clamp or clamps at one end of the frame. The irregular or neck end was then gripped by one or more independently movable stretching members and tension or pull 40 was applied separately to these members to stretch separately the different longitudinally extending portions of the width of the hide engaged thereby. After one longitudinally 45 extending portion of the hide was stretched sufficiently the stretching member engaging that portion was clamped or otherwise maintained in fixed position to hold that portion as stretched, and then another longitudinally extending portion of the hide 50 was likewise stretched and this operation

was repeated until the entire width of the hide had been stretched to render it uniform in strength and elasticity throughout. With the operation just described obviously 55 the task of judging the tensile strength and amount of stretch in the different parts of the hide was left to the operator.

The object of my invention is to provide in a hide stretcher an automatic mechanism whereby all longitudinally extending portions of the width of the hide will be subjected to equal stretching pull or tension of a predetermined amount so applied that the portions will be simultaneously stretched, regardless of the relative tensile strength 60 thereof, throughout the different distances required to render the stretched hide uniform in strength and elasticity.

Other features and objects of my new and improved hide stretcher will be brought 65 out in the detailed description of its construction and operation given below.

Referring to the two sheets of drawings in which similar characters indicate similar parts Fig. 1 is a plan view of a device 70 embodying my invention; Fig. 2 is a sectional view along the lines 2-2 in Fig. 1; Fig. 3 is a plan view showing the construction of a movable stretching member and automatic stop therefor; and Figs. 4 and 5 show 75 further details of construction.

Referring to the drawings the hide stretcher shown therein has been reduced for the sake of clarity to its simplest form and consists of a stretching frame and a detachable stretching head. The stretching frame 1 may be of either wood or metal or a combination of both, with side pieces 2 and 3 and end pieces 4 and 5. The end piece 4 of the frame 1 contains one or more fixed 80 members to hold one end of the hide, as described below and in this embodiment they are in the form of fixed clamps 6 which are spaced apart and are held in position by bolts 7 extending through the side piece 85 4. The clamps 6, as shown in Fig. 4, each comprise a pair of plates 8 which are serrated on their inner faces and are otherwise adapted to grip and hold a portion of the hide when the plates are brought together 90 95 100

by bolts 9 acting about a fulcrum lug 10 extending inwardly from the inner face of one of the plates.

At the other end of the stretching frame 5 and on the end piece 5 thereof are mounted a plurality of independently movable stretching members which in this embodiment of my invention each consist of a clamp 11 and a stretching rod 16. The 10 clamps 11 are mounted in any convenient way on the inner end of the rods 16 and consist of a pair of plates 12 carried by a bolt 13 extending through a longitudinally arranged slot 14 in the end piece 5, for the 15 purpose more fully outlined below. The plates 12 are serrated on their inner faces and are adapted to be brought together to grip a hide by a pair of bolts 15 working about a fulcrum lug 15^a. The stretching 20 rods 16 are ratcheted as at 17 and extend through the automatic stop members 18 each of which, preferably, includes a spring detent 19 positioned to engage the ratchets of a rod 16 and to prevent the rod from being 25 moved towards the center of the stretching frame 1 unless the detent is manually released, all as clearly shown in Figs. 2 and 3.

The stretching head in this embodiment of my invention comprises a base 20 and 30 spacing blocks 21 to maintain the base in predetermined fixed relation to the stretching frame 1. Upon the base 20 are mounted a plurality of cylinders 22 arranged in longitudinal alignment with the stretching frame and containing fluid actuated pistons 23 carried on the end of piston rods 24 which terminate at their opposite ends as eyes 25 adapted to engage hooks 26 on the ends of the stretching rods 16. Leading into each 35 of the cylinders 22 is a fluid feed pipe 27 connected to a main pipe 28 which received fluid under pressure from a master cylinder in which pressure is created by the master piston 30. When the master piston 30 is 40 moved in the master cylinder 29 to force the fluid 31 outwardly therefrom this fluid will flow through the main 28 and through the fluid feed pipes 27 into each of the cylinders 22 in front of the pistons 23 and these pistons 45 will be moved rearwardly in the cylinders with a force or pull equal to the pressure on the fluid in the master cylinder. It may be understood that a uniform pull will be exerted upon all of the stretching members 50 operatively connected to the piston rods and in turn a uniform pull or tension will be applied to stretch the hide. Also, irrespective of the distances traveled by the different pistons 23 in stretching the hide, the 55 actuating pressure for all the pistons, and in turn the tension on the hide will remain the same.

Having described the component parts of my device I will now more fully explain 60 its mode of operation, which is as follows:

The hide 32 is placed in the stretching frame and the straight end thereof is gripped in the clamps 6 at the end 4 of the frame. The irregular or neck end of the hide is then gripped by the clamps 11 carried by the stretching rods 16. The stretching head is then placed in position at the end 5 of the stretching frame 1 and the hooks 26 on each of the stretching rods 16 are inserted through an eye 25 on one of the piston rods 24 which rods are freely movable when there is no fluid in the cylinder 22. If it is necessary to move the rods 16 inwardly to bring the clamps 11 on the end thereof in contact with the hide the spring detents 19 may be temporarily released by lifting up on the catch 33.

When each of the stretching rods 16 has been engaged by a piston rod 24 pressure is applied to the fluid 31 by movement of the master piston 30 through an outside force of power, not shown here, and the fluid 31 is forced from the cylinder 29 through the main pipe 28 and through the fluid feed pipes 27 into the cylinders 22 in front of the pistons 23 to move the pistons and the piston rods 24 carried thereby away from the stretching frame 1. When the piston rods move in this manner pull or tension is applied through the stretching rods 16 to the various longitudinally extending portions of the hide 32. A pressure gauge 34 may be provided on the master cylinder 29 whereby the operator may determine the fluid pressure being exerted against the pistons 23 and, therefore, may determine the pull being applied to the hide. A port 35 may be provided in each of the cylinders 22 to allow the escape of air therefrom as the piston is moved therein. Likewise, a valve 36 may be provided in each of the fluid feed pipes 27 so that a flow of fluid to any of the cylinders 22 may be cut off if desired. The movement of the stretching members in stretching the hide will be steadied by the bolts 13 of the clamps 11 moving in the slots 14.

As mentioned above the pistons 23 will move rearwardly in their cylinders 22 and move the piston rods 24 and stretching rods 16 different distances for a given pressure being applied as shown by the gauge 34. The movement of a piston will continue until the longitudinally extending portion of the hide gripped by the clamp 11 on the end of the stretching rod 16 actuated by that piston will stretch no further under the applied pressure. However, a piston 23 exerting pull on a portion of the hide at the belly side thereof will move a great deal further than the piston exerting pull on a portion of the hide at the back side thereof, but the pressure exerted on the pistons and in turn the pull or tension exerted on the 130

various portions of the hide will be uniform.

After a sufficient pressure as indicated by the gauge 34 has been applied to the pistons 23 and in turn after a sufficient stretching pull or tension has been applied to the hide the movement of the master cylinder 29 is stopped and the stretching head is removed from the stretching frame and the piston rods 24 are taken out of contact with the stretching rods 16. When the head is removed the hide will be maintained in stretched position by the detents 19 of the stops 18 acting on the ratchets 17 in the upper surface of the stretching rods 16. It may be readily understood that in adapting my invention to hide stretchers of various types the details of construction such as the size, shape and arrangement of parts may be varied within wide limits without deviating from the spirit of my invention as included in the claims set forth below.

What I claim as new and desire to secure by Letters Patent, is:

1. A hide stretcher comprising in combination a stretching frame having a fixed member for holding one end of said hide and a plurality of independently movable stretching members to engage the other end thereof, and a stretching head having a plurality of stretching means each comprising a piston in a cylinder, each of said pistons being operatively attached to one of said stretching members, said stretching means including means for feeding a fluid under pressure into said cylinders and thereby being arranged to exert automatically and simultaneously a uniform tension on said stretching members but to allow said stretching members to be moved different distances thereby, and automatic stops co-operating with said stretching members to maintain said hide in stretched position.

2. A hide stretcher comprising in combination a stretching frame having a fixed member for holding one end of said hide and a plurality of independently movable stretching members to engage the other end thereof and a plurality of stretching means arranged to move said stretching members to stretch said hide, each of said stretching means being operated by a piston movable in a cylinder, and a master cylinder and means for injecting fluid under pressure therefrom into said other cylinders to move said pistons whereby said stretching means will exert automatically and simultaneously a uniform tension on said stretching members but will allow different portions of said hide engaged by different stretching members to be stretched different distances thereby.

3. A hide stretcher comprising in combination a stretching frame having a fixed member for holding one end of said hide

and a plurality of independently movable stretching members to engage the other end thereof and a plurality of stretching means each of which is operatively connected to one of said stretching members, each of said stretching means being operated by a piston movable in a cylinder whereby said stretching member is moved to stretch the portion of hide in engagement therewith, a master cylinder and means for injecting fluid at a desired pressure therefrom into said other cylinders to move said pistons whereby said stretching means will exert automatically and simultaneously a uniform tension on said stretching members but allow said stretching members to be moved different distances thereby.

4. A hide stretcher comprising in combination a stretching frame having a fixed member for holding one end of said hide and a plurality of independently movable stretching members to engage the other end thereof and a plurality of stretching means each of which is operatively connected to one of said stretching members, each of said stretching means being operated by a piston movable in a cylinder whereby said stretching member is moved to stretch the portion of hide in engagement therewith, a master cylinder and means for injecting fluid at a desired pressure therefrom into said other cylinders to move said pistons whereby said stretching means will exert automatically and simultaneously a uniform tension on said stretching members but allow said stretching members to be moved different distances thereby, and automatic stops co-operating with said stretching members to maintain said hide in stretched position.

In witness whereof I have signed my name to the foregoing specification.

HERBERT DE STAEBLER.
